DESIGN FOR A PANTY GIRDLE OR SIMILAR ARTICLE

Samuel L. Welsch, Brooklyn, N. Y., assignor to Lewel Mfg. Co. Inc., New York, N. Y., a corporation of New Jersey

Application December 18, 1941, Serial No. 104,713

Term of patent 7 years

To all whom it may concern:

Be it known that Samuel L. Welsch, a citizen of United States and resident of Brooklyn, in the county of Kings and State of New York, has invented a new, original, and ornamental Design for a Panty Girdle or Similar Article, of which the following is a specification, reference being had to the accompanying drawing, forming part thereof, and in which,

Fig. 1 is a front perspective view of a panty girdle, embodying my new design; and

Fig. 2 is a rear perspective view of the same.

I claim:

The ornamental design for a panty girdle or similar article, substantially as shown.

SAMUEL L. WELSCH.
